UNITED STATES PATENT OFFICE.

JOHN ASTROM, OF FORT WAYNE, INDIANA.

INTERNAL-COMBUSTION ENGINE.

Application filed March 23, 1923. Serial No. 627,051.

This invention relates to internal combustion engines.

In internal combustion engines as heretofore constructed, difficulty has been experienced, due to the vibrating of the parts when critical speeds are reached, which has been found due, in large measure, to the reciprocating valve actuating parts. The cylinders are, due to the side thrust of the pistons, subjected to unequal wear and unequal pressure which, combined with the unequal heating, as most of the heat is concentrated towards the exhaust, soon cause the cylinder to get out of true with consequent detrimental results. Further, the unequal pressure and intense heat cause improper or unequal distribution of the lubricant.

This invention is designed to overcome the above noted defects and objects of such invention are, therefore, to provide an internal combustion engine in which vibration

does not occur at critical speeds, in which the wear of the cylinder and associated parts is substantially uniform, in spite of the side thrust of the pistons, in which the heat is substantially uniformly distributed throughout the cylinder walls, and in which an even lubrication is secured.

Further objects are to provide an internal combustion engine in which the valves have substantially uniform speed irrespective of the changing speed of the piston from instant to instant, in which ample port opening is provided and wire drawing prevented, in which friction of motion alone occurs, although the piston dwells at each end of its stroke as the crank passes dead center, in which there are no reciprocating parts for actuating the valves, and in which the valve actuating mechanism and valves move continuously in one direction.

An embodiment of the invention is shown in the accompanying drawing, in which:—

Figure 1 is a vertical elevation through the engine, such view corresponding roughly to a section on the line 1—1 of Figure 2.

Figure 2 is a sectional view on the line 2—2 of Figure 1, showing the parts at the beginning of the suction stroke.

Figures 3, 4 and 5 are fragmentary views corresponding to Figure 2 and showing the position of the parts at the end of the suction stroke at the completion of the compression stroke and at the end of the explosion, or working stroke.

The engine comprises a cylinder 1 provided with suitable water jackets 2 and with an inlet and an exhaust port, indicated respectively at 3 and 4, the exhaust port in the form shown being larger than the inlet port and both such ports being preferably of substantially rectangular outline with the longer dimension paralleling the axis of the cylinder. The cylinder is completed by a cylinder head 5 which is provided with a tubular depression 6 adapted to accommodate the spark plug and with an enclosing hood 7 contacting with the upper portion of the cylinder body and held in place by a nut 8' screwed upon the upwardly projecting tubular portion of the cylinder head—such hood providing the necessary water jacket for the cylinder head.

It is to be noted that the inlet and exhaust ports 3 and 4 are slightly offset from a diametrically opposed location, as may be seen from Figure 2. The purpose of such spacing will hereinafter appear.

Within the cylinder a sleeve, or liner 8 is revolvably mounted and is provided with a pair of rectangular openings 9 and 10 which, as may be seen from Figure 2, are duplicates and have a diametrically arranged relative position. These openings also have their longer dimension paralleling the axis of the cylinder. They are, however, of the same size. This sleeve projects beyond the lower end of the cylinder and is retained in place by means of an outwardly projecting radial flange 11 which cooperates with any type of retaining member, such as indicated by the bracket at 12. The lower portion of this sleeve is provided with worm teeth 13, as may be seen from Figure 1.

Within the sleeve a piston 14 is reciprocally mounted and is connected by means of a pitman 15 with the crank 16 of the engine shaft, or crank shaft 17, such shaft being conveniently mounted within bearings carried by the crank case 18. The usual oil pan 19 may completely seal the crank case, as illustrated in Figure 1.

Any desired means may be provided for driving the sleeve 8 from the crank shaft. In the form shown, a worm 20 is arranged in cooperative relation to the worm teeth 13 and is driven by means of a silent chain 21 from the engine shaft. In the form shown, the gear ratio between the engine shaft and the sleeve 8 is such that the sleeve 8 executes one complete revolution for four revolutions

of the engine shaft, although obviously this relative ratio may be varied by varying the number and arrangement of ports, or openings, or both.

5 The operation of the engine is as follows: In the position shown in Figure 2, the suction stroke is just beginning. As the crank shaft rotates, the sleeve 8 moves in the direction of the arrow, thereby rapidly opening 10 the inlet port, while the piston is slowly beginning its downward stroke. At the end of the suction stroke, the sleeve occupies the position shown in Figure 3 and it will be seen, just closes the inlet port 3. As the piston ascends, executing the compression stroke, the sleeve moves in the direction of 15 the arrow, finally arriving at the position indicated in Figure 4 with a relatively large overlap for the valve secured by the wide 20 spacing between the opening 9 and the inlet and exhaust ports. At this point the explosion takes place and the piston travels downwardly upon its working stroke. As the piston nears the lower end of its working 25 stroke, the exhaust port 4 is uncovered by the valve, or sleeve 8, as the opening 9 passes over such exhaust port, as indicated at Figure 5. It is to be noted that the center line of the exhaust port is spaced from 30 the center line of the inlet port an angular distance less than 135°. Due to the offset position of this exhaust port and its relatively greater width, this initiation of the opening of such port occurs prior to the completion 35 of the working stroke and allows a rapid and complete discharge of the gases, thereby relieving any back pressure prior to the beginning of the upward stroke of the piston. The piston now travels upwardly and forces the burned gases through the 40 exhaust port, thereby completely cleaning the cylinder. At the completion of this last stroke of the piston, the ports occupy the position indicated in Figure 2, except that 45 the openings 9 and 10 in the sleeve have changed positions.

It is, of course, appreciated that the sleeve 50 may be given other rates of rotation with reference to the crank shaft and that the openings in such sleeve may be correspondingly varied. Also, it is to be noted that multiple inlet and exhaust ports may be provided in the cylinder and the openings in the sleeve correspondingly increased.

55 It is to be particularly noted that there are no reciprocating valves, nor reciprocating mechanisms, for operating the valves, but that the sleeve rotates continuously in a uniform manner and in the same direction. 60 It will be seen, therefore, that no undesirable vibration of the engine is produced at certain or critical speeds, but that the engine will run smoothly at all speeds.

It is also to be noted that the revolving

sleeve uniformly distributes the heat 65 throughout the cylinder walls and prevents uneven heating of such walls and facilitates radiation.

It is to be further noted that although side thrust of the piston necessarily occurs, 70 this side thrust is borne by different portions of the sleeve 8, as such sleeve rotates and, consequently, the wear is uniformly and evenly distributed and there is not, therefore, the tendency to wear the cylinder 75 and piston into an oval-shaped cross sectional contour.

It is, of course, intended that any desired system of lubrication may be employed with 80 this engine and it is to be noted that the uniformly rotating sleeve distributes the lubrication evenly over the walls of the cylinder and over the piston.

It is further to be noted that other means 85 may be employed than that shown to revolve the sleeve.

Although a single cylinder engine has been illustrated, it is obvious that this invention is admirably adapted to multi-cylinder engines. In such case, the worm shaft 90 is extended and all of the worms are mounted upon this shaft in an obvious manner, the worms being opposed so as to balance the axial thrust upon the shaft.

Although one form of the invention has 95 been described in considerable detail, it is to be understood that the invention may take various forms and, therefore, such invention is to be limited only as set forth in the appended claim.

I claim:—

An internal combustion engine comprising a cylinder having inlet and exhaust ports, a sleeve revolvably mounted within said cylinder and extending to adjacent the upper end of said cylinder, a piston mounted within said sleeve, a crank shaft operatively coupled to said piston and said sleeve, and a cylinder head having a downwardly projecting portion accurately conforming in part to the upper end of said sleeve and having an outwardly extended flange adapted to be directly bolted to said cylinder adjacent the upper end of said sleeve, said cylinder head having a depressed well extending downwardly into said cylinder and having a threaded lower aperture adapted to receive a spark plug, whereby an inserted spark plug is positioned directly opposite said inlet and outlet ports, said well being surrounded by an outwardly projecting cylindrical shell provided with an externally threaded outer portion.

In testimony that I claim the foregoing I have hereunto set my hand at Fort Wayne, in the county of Allen and State of Indiana.
